[57] CLAIM

The ornamental design for a cigarette holder, as shown and described.

DESCRIPTION

FIG. 1 is a rear elevational view of a cigarette holder, showing our new design;

FIG. 2 is a side elevational view, the opposite side being a mirror image thereof;

FIG. 3 is a front elevational view thereof;

FIG. 4 is an end elevational view thereof, taken from the top of FIG. 1;

FIG. 5 is an end elevational view thereof, taken from the bottom of FIG. 1;

FIG. 6 is a rear perspective view thereof;

FIG. 7 is a front perspective view thereof.

FIG. 1

FIG. 3
